UNITED STATES PATENT OFFICE.

FRANK P. MILLER, OF CHICAGO, ILLINOIS.

ACCESSORY CONTAINER FOR RAILWAY USE.

Application filed July 17, 1925. Serial No. 44,168.

This application relates to improvements in accessory container for railway use, and refers more particularly to a unitary construction taking the form of a container 5 adapted to carry various signal and safety appliances and accessories used by the employees of railroads, particularly by brakemen and flagmen.

The rules and regulations governing the 10 operation of railroads require that certain signal and safety appliances and accessories must be provided for the use of brakemen and flagmen, such as the red flag, danger lights and torches, torpedoes, matches and 15 the like. These accessories are inconvenient to carry, because it is difficult to distribute them in the pockets of clothes and it frequently happens that the article required is missing when the emergency arises for its 20 use. This is particularly true in rainy weather and at night. Oftentimes, an employee will be using a lantern and daylight comes before the emergency is over, and he is without his red flag. Torpedoes being 25 small, are lost through holes in pockets or fall out when the carrier bends over. The sharp points on the signal torches tear the clothes and sometimes inflict physical injury to the carrier.

30 To overcome the above difficulties and many others, I have conceived a container taking the form of an elongated tube divided into compartments, and having its ends closed by removable caps. The red flag 35 and signal lights are kept in separate compartments of the tube; torpedoes may be kept in one end closed by the cap; matches or other small accessories may be kept in the other end.

40 Various other objects and advantages will be apparent from the following description.

In the drawings:

Fig. 1 is an exterior plan view of the appliance.

45 Fig. 2 is a cross sectional view taken on line 2—2 of Fig. 1, looking in the direction of the arrows.

Fig. 3 is an enlarged view of one end of cap.

50 Figs. 4 and 5 are respectively cross sectional views taken on lines 4—4 and 5—5 of Fig. 3, looking in the direction of the arrows.

Fig. 6 is a cross sectional view taken on line 6—6 of Fig. 4.

Fig. 7 is a cross sectional view taken on line 7—7 of Fig. 2.

Fig. 8 is a side elevational view of one form of adjustable flag staff and flag. 60

Fig. 9 is a top plan view of the construction shown in Fig. 8.

Fig. 10 is a side elevational view of another form of adjustable flag staff and flag.

Fig. 11 is an enlarged sectional view 65 showing the adjustable construction shown in Fig. 10.

Fig. 12 is a cross sectional view taken on line 12—12 of Fig. 11.

Referring in detail to the drawings, 1 designates as a whole the container which is preferably cylindrical in form having end closing caps. The container comprises a hollow cylindrical tube 2 having the integrally formed outwardly extending circum-

ferential ribs or flanges 3 substantially immediately adjacent the ends. The tube may be of cast aluminum or other non-rusting metal; it being desirable to combine in the container maximum strength with minimum 80 weight.

A dividing partition plate 4 is inserted in the grooves 5 extending longitudinally of the tube, said partition dividing the interior of the tube into compartments. It is understood that any number of compartments may be provided by increasing the number of partition plates 4. One end of the tube is closed by means of the plate 6 and auxiliary flanged plate 6^a where the latter is desirable, plate 6 being preferably 85 made integral with the tube. This end of the device is adapted to be closed by the removable cap 7 having ring 8, the latter connecting with ring 9 on one end of chain 10.

The opposite end of chain 10 has ring 95 11, adapted to connect with ring 12 on the tube 2. It will be readily seen that when the cap 7 is removed from the end of the device, that it will not be lost, due to the anchoring chain 10. The cap may be locked in position on the end of the tube 2 by means of the pin 13 protruding from the surface of the end of the tube registering with angled slot 14 on the cap 7.

Torpedoes designated 15 may be placed in the compartment formed 100 on the end of the tube just described, this end of the device being held upright when

105

110

115

120

125

the cap is taken off to prevent torpedoes from falling out. It is understood, of course, that small appliances other than torpedoes may be kept in this end of the device, and 5 the use of torpedoes is merely illustrative.

Referring now to the opposite end of the device, it will be instantly noted that this end is formed differently from the other, not being closed by closure plates similar to 10 6 and 6', but is left entirely open. This end is closed by the closure cap 16 having ring 17 connected with a free ring 18 attached to one end of a chain 19. The other end of chain 19 has a similar free ring 20 connected with ring 21 protruding from the 15 surface of the tube. The cap 16 is provided with the angled slot 22 adapted to register with pin 23 on the end of the tube to lock said cap on that end. The circumferential 20 ribs 3 prevent excess inward movement of the caps 7 and 16 on the ends.

The cap 16 may be provided with the outer closure plates 24 and 25 mounted in the interior thereof. The outer plate 25 is preferably centrally apertured as shown at 26. In the separate compartments formed by the 25 partition plate 4 are adapted to be inserted from the free end of the tube the flagstaff and flag designated as a whole 27 and the 30 red signal torches 28.

Describing now more in detail the construction shown in Figs. 3 to 6, in the compartment formed between the plates 24 and 25 is adapted to be inserted the metal box 35 29 which is a three sided substantially rectangular box having an open top. The front of the box is provided with the flanged extensions as shown at 30 in Fig. 5, which preferably conform in shape with the shape of 40 the cap, setting in the grooved face of the cap so that the front faces of the flanged extensions are flush with the wall of the cap, the wall of said cap being provided, of course, with the opening into which the box 45 is inserted. The front portion of the box is provided with the knob handle 31 to facilitate the movement of the box. The upper end of the front end of the box is provided with the forwardly facing flange 32 50 dished on its upper surface as shown at 33 to register with the locking stud 34 held under spring tension by coil spring 35. A hollow housing 36 is provided, preferably as an integral part of the upper end of the cap 55 16 in which the spring 35 and stud 34 are mounted. The front face of this housing is slotted as shown at 36 to allow for movement of the pin 37 screw threaded on the stud 34. This pin and slot arrangement prevents 60 the stud 34 and spring 35 from dropping into the box 29 when the latter is withdrawn. A lug 38 is screw threaded into the bottom of the box 29 which is adapted when the box 65 is withdrawn to abut against the front wall closing the opening 26, preventing the box

from being entirely withdrawn. The advantage of this feature will be instantly apparent. The match box can be readily opened or closed; in open position, means are provided for preventing the box from 70 being entirely withdrawn and the box or matches lost; and in closed position, it is securely locked.

Describing now the collapsible flagstaff, it is preferably made in two pieces, an elongated solid stem 39 of restricted cross sectional width or diameter is adapted to be slid into and out of the telescoping sleeve 40. In the construction shown in Figs. 8 and 9, a screw 4 preferably having an enlarged 75 head is threaded to the stem 39, said lug being adapted to register with the elongated slot 42 in the telescoping sleeve 40. The arrangement is such that stem is adapted to slide freely into and out of the sleeve, but is 80 prevented from being entirely withdrawn. It is impossible therefore, for the stem to be accidentally displaced entirely from the sleeve holder. The flag 43 may be attached by means of the rings 44 at both ends of the 85 flag, and preferably at an intermediate point as shown, by attaching the outer end of the flag to the outer end of the stem at point 45, to an intermediate point 46 on the stem, and the inner end of the flag at the point 47 on 90 the sleeve. Rings 45 and 47 are fixedly attached respectively to the stem and sleeve, whereas ring 46 is movable on the stem. When it is desired to push the stem into the 95 sleeve, the movable ring 46 slides forward on 100 the stem, and the flag is drawn together in plait form to the position shown in dotted lines in Fig. 8. The flag is then folded around the upper part of the sleeve and is ready to be placed in one compartment of 105 the container.

A slightly modified form of construction is shown in Figs. 10 to 12. The forward end of the sleeve 40 is provided with longitudinal slots 48 and may taper inwardly in an 110 outward direction, shown clearly in the cross section shown in Fig. 11. The sleeve may be externally screw threaded as shown at 49 adapted to register with the internal screw threaded portion 50 on the tightening 115 nut 51. By rotating the nut 51 and decreasing or increasing the width of the slots 48, the degree of friction tension between the stem and sleeve can be carefully controlled. Thus it is possible to lock the stem in the 120 sleeve in extended as well as inoperative position.

A strap 52 having clamps or rings 53 may be attached to the rings 12 and 21 to assist in carrying the container, which can be slung over the shoulder and out of the way, allowing freedom for the hands for carrying a lantern and the like. One use for the matches in box 29 is for lighting the signal lantern. Where electric lanterns are used, 125 130

batteries may be carried in box 29. Fuses for electrical use may be carried in the compartment which has been illustrated as containing torpedoes.

5 The container as shown in Figs. 1 and 2 is very light and is constructed entirely of metal. The filled container is adapted to be held in place in a car in a horizontal position between spring tensioned clamps.

10 I claim as my invention:

1. In a railway appliance, the combination with an elongated tube internally divided into longitudinal compartments by a longitudinal partition element, said tube having a closed end and an open end, and removable caps adapted to have engagement with both the open and closed ends of the tube.

2. In a railroad appliance, the combination with an elongated hollow container interiorly divided into longitudinal compartments having one closed end formed by a closure element and an open end, of removable closure caps adapted to close both ends of the container, said container having a continuation beyond the closure element, providing an auxiliary compartment for holding small accessories for railroad use.

3. In a railway appliance, the combination with an elongated tube internally divided into longitudinal compartments by a longitudinal partition element, said tube having a closed end and an open end, and removable caps adapted to have engagement with both the open and closed ends of the tube, one of said caps being provided with means whereby it serves as an auxiliary compartment for holding small accessories.

4. In a railroad appliance, the combination with an elongated hollow container interiorly divided into longitudinal compartments having one closed end formed by a closure element and an open end, of remov-

able closure caps adapted to close both ends of the container, said container having a 45 continuation beyond the closure element, providing an auxiliary compartment for holding small accessories for railroad use, and a movable container in the cap closing the opposite end adapted to contain small 50 accessories.

5. A collapsible staff for railroad signal flags, comprising a sleeve and a stem movable therein, of means fixed both to the stem and to the sleeve to which portions of a signal flag are attached, an element movable on the stem between the said fixed means also attached to the flag at intermediate portions thereof, means for preventing the stem from being withdrawn entirely from 60 the sleeve, including means for locking the stem in the sleeve in either extended or telescoped position.

6. A collapsible staff for railroad signal flags, comprising a sleeve and a stem movable therein, of means fixed both to the stem and to the sleeve to which portions of a signal flag are attached, an element movable on the stem between the said fixed means also attached to the flag at intermediate portions thereof, means on the stem registering with means on the sleeve for preventing the stem from being withdrawn entirely from 65 the sleeve, including means for locking the stem in the sleeve in either extended or telescoped position.

7. In a railroad appliance, the combination with an elongated tube internally divided by a longitudinally extending partition into compartments, closure caps for each end of said tube adapted to have cooperative engagement therewith whereby there is provided auxiliary compartments for holding small accessories for railroad use.

FRANK P. MILLER.
